DESIGN FOR A SMOKING STAND

Onnie Mankki, Cleveland Heights, Ohio

Application March 14, 1938, Serial No. 75,807

Term of patent 7 years

To all whom it may concern:

Be it known that I, Onnie Mankki, a citizen of the United States, residing at Cleveland Heights, in the county of Cuyahoga, State of Ohio, have invented a new, original, and ornamental Design for a Smoking Stand, of which the following is a specification, reference being had to the accompanying drawing, forming part thereof.

I claim:

The ornamental design for a smoking stand, as shown.

ONNIE MANKKI.
